UNITED STATES PATENT OFFICE.

GEORGE D. SPOONER, OF RUTLAND, VERMONT.

CANCELING-STAMP.

SPECIFICATION forming part of Letters Patent No. 247,961, dated October 4, 1881.

Application filed March 5, 1881. (No model.)

To all whom it may concern:

Be it known that I, GEORGE D. SPOONER, a citizen of the United States, residing at Rutland, in the county of Rutland and State of Vermont, have invented a new and useful Improvement in Canceling-Stamp for Postal and other Canceling Purposes, of which the following is a specification.

My invention relates to stamps which cancel by cutting or perforating the stamps on letters or other objects, and which are provided with means for imparting rotary and descending movements to the cutter or perforator in the act of cancellation, and reverse movements to the same after the cancellation has been effected.

My invention consists, mainly, in the central guiding-stem; also, in means for guiding the stamp-head, both on its outside and inside; also, in means for steadyng and balancing the stamp; also, in an improved construction of cutter, with means for determining the depth of its cut into the paper; and also in means for determining the vertical movement of the cutter independent of the cutter-head, and at the same time insuring by said means a centralization of the spirally-threaded tube and consequent movement of the stamp-head on a line parallel with the central guiding-stem.

The drawings represent a vertical section of my improved stamp in two conditions, Figure 1 showing it as it appears before pressure or force is applied to its handle for the purpose of canceling a stamp, and Fig. 2 showing it as it appears after such force has been applied. In Fig. 2 the line of section is at right angles to that of Fig. 1, and only the handle, stamp-head, and its guide are sectioned. Fig. 3 is a bottom view of the stamp; Fig. 4, a detail broken section of the stamp-head and its guide slightly modified in construction, in order to admit of the use of a marking-cork or india-rubber block on the left-hand side of the stamp; and Fig. 5 is a top view of Fig. 4.

The stamp represented is in many respects very similar to the one patented by me June 29, 1880, and my improvements are specially applicable to said stamp, but not confined wholly to the same.

A is a central guiding-stem; B, the handle, provided with a central metal ring or tube, α ,

through which the stem A plays freely, and by which it is centered and guided in the handle.

C is the stamp-head, formed with a bottom shoulder, b , a top shoulder, c , and an intermediate shoulder, d . A short spiral spring, f , rests on the shoulder d , and a tubular plunger, d' , rests down upon this spring and has its movement limited by the shoulder c . On the lower end of the central stem, A, a screw-thread, g , is formed; and at the point where the jam-nut h is applied a screw-thread, i , is also provided on said stem. The spirally-threaded tube D, which rotates the stem A, encircles the stem and fits within the actuating-nut E, which is secured into a tubular guide, F, and has the handle B screwed to it, as shown. The regulation or jam nut h extends down into the spirally-threaded tube D, and thereby centers this tube with the stem A. The said tube D is formed with a shoulder or collar, j , which fits a counter-bore of the hollow plunger d' . Below the shoulder j the tube D fits snugly in the stamp-head C and screws upon the screw-thread g , as shown.

In the lower end of the stem A a conical cutter, l , is screwed, and in the cylindrical part of this cutter a set-screw, k , is applied, as shown. The conical cutter is kept from moving above the shoulder b of the cutter-head by means of a flange, l' . This flange may be a detachable nut or other suitable device which will bear against the shoulder b of the stamp-head. The cutter l , being tapering in its outer side and cylindrical on its inside, is brought to a fine sharp edge. The head of the screw k , being of greater diameter than its body and of less depth than the conical part of the cutter, is made to serve as a gage for increasing or decreasing the depth of the cut into the paper or stamp being canceled.

The amount of downward movement produced by the pressure exerted upon the handle of the stamp is regulated by the jam-nut h and screw g , and it is controlled while the stamp is being used by the spring f and the hollow plunger d' . The height of the jam-nut and the adjustment up or down of the spirally-threaded tube, determines the extent of the independent movement of the stem A and cutter l . The guide F is extended down in form of a cylinder, and is slotted at m , in order to

accommodate the arm G of the stamp-head. It also is notched at m' , in order to accommodate a foot, G', of said head. This guide F, by fitting over the arm G, serves for holding 5 the nut E from turning while the screw-thread of the tube D is turning in said nut. It also serves for assisting the guide a in holding the canceling-cutter in a true central position with respect to the head C, and for steadyng and 10 also guiding the tubular guide F. A shoe, H, is fastened by a set-screw, o, upon the foot G', and made adjustable toward the stamp-head by means of a slot, p, in said foot. This foot and the shoe-piece may be constructed as shown 15 in Figs. 4 and 5, and thus made to serve for holding a marking-cork or other device, r, as well as serve for balancing the stamp and guiding the tubular portion F. Two set-screws, o, and two slots, p, will be adopted when the 20 construction shown in Figs. 4 and 5 is employed. The shoe and its attachments may be made of such proportions with respect to the arm G and its attachments that the stamp will be balanced—that is to say, the shoe H may 25 form a lateral bearing for the stamp proper—and when the stamp is forced downward upon a letter or other object this shoe, by bearing down upon the letter, will prevent the stamp from canting, and thus insure a perfectly horizontal contact between the stamp and letter. 30 Where an arm, G, with marker attached to it is used the stamp is thrown out of balance, and to counteract this the foot G' is applied on the opposite side of the stamp-head at a point directly opposite said arm G, as shown in Figs. 35 1, 4, and 5, said shoe serving also as a support for the guiding-shoe H, which in turn acts as a steadyng and guiding means to the pend-ent tube F, as shown.

40 Between the jam-nut h and the guide a of the stamp is applied the usual spring, I, for returning the handle and cutter to their normal positions.

The construction and operation of the parts 45 described is such, as will be evident from the drawings, that when the handle is forced downward the cutter and its stem will make an independent vertical movement to the extent that is desired to cut into a postage-stamp or 50 other object, and instantly thereupon it will be caused to revolve and cut out the paper, and in this revolving movement the vertical movement may, if necessary, be increased by pressing forcibly upon the stamp-handle; but

such vertical movement is limited to the distance between the plunger d' and shoulder c, which distance can be regulated with great nicety by the jam-nut h and the screw-thread g on the stem A. 55

The greatest advantage of my present invention is secured from the adjustment of the spirally-threaded tube upon the central guiding-stem by means of the screw g, as by this means the stem is made available for centralizing, supporting, and guiding all the parts, 60 so that bind cannot take place.

The stamp-head and other parts may be on their external surfaces square instead of round, if desirable. In some uses of the stamp described the arm G and foot G' might be unnecessary, and those parts might be left off in the construction without departing from other portions of my invention. 70

What I claim as my invention, and desire to secure by Letters Patent, is— 75

1. The combination of the stem A, carrying a canceling-cutter and having screw-threads i and g, jam-nut h, screw-threaded tube D, nut E, stamp-head C, plunger d', and handle B, substantially as and for the purpose described. 80

2. The combination of the stamp-head C, central stem, A, tubular guide F, screw-threaded tube D, nut E, shoe H, and handle B, having a guide, a, substantially as and for the purpose described. 85

3. The screw-threaded tube, fitted around the jam-nut h and centered by it, and fastened by a screw-thread, g, to the stem A, substantially as described.

4. The tubular guide F, fastened to the nut E, in combination with the adjustable shoe H, and the stamp-head C, having attached to it the foot G', substantially as described. 90

5. The foot G', in combination with the stamp-head C, having an arm, G, whereby the stamp is steadied and balanced and facilities are afforded for attaching a shoe, H, and marking-cork, substantially as described. 95

6. The hollow conical cutter l, provided with a central or gage set-screw, k, substantially as and for the purpose described. 100

Signed in presence of two subscribing witnesses.

GEORGE D. SPOONER.
